UNITED STATES PATENT OFFICE

2,577,556

CARTRIDGE SYRINGE, INCLUDING A
CANNULA ATTACHING CHUCK

David C. Williams, Needham Heights, Mass., assignor to MacGregor Instrument Company, Needham, Mass., a corporation of Massachusetts

Application February 4, 1950; Serial No. 142,410

6 Claims. (Cl. 128—218)

1

My present invention relates to cartridge syringes and particularly to novel chuck means therefor that enable the needles for use with such syringes to consist simply of cannulae pointed at both ends.

It has long been the practice for cartridge syringes, which because they are widely used in the dental field are commonly called dental syringes, to provide needles consisting of cannulae completed by providing them with so-called "head shells" intermediate their pointed ends. The reason for that construction is that the conventional cartridge syringe receives a cartridge closed at its front end by a diaphragm and at its rear end by a stopper and when the syringe is assembled for use, that cartridge is thrust forward into a seated position. The cannula receiving bore in the syringe tip has a seat for the head shell so that when the head shell is clamped against its seat by a nut threaded on the syringe tip, the cannula is securely locked to the syringe with its rear end entrant of the syringe to pierce the diaphragm of the cartridge as it is seated. The stopper of the cartridge acts as a plunger when engaged and driven forward by the syringe piston.

While such needles have proved satisfactory in that they were adapted to be securely locked to cartridge syringes, they are relatively expensive due to the fact that the head shells are separately formed from tin or lead and then slipped onto and swaged to the cannulae. It is the principal objective of this invention to provide means whereby needles for cartridge syringes may be simply cannulae of suitable tubular stock of desired length and pointed at both ends, and be securely locked to the tips of cartridge syringes as such cannulae may be easily and efficiently produced to sell at such a low cost that dentists or other users will, as a matter of course, discard them after single use ensuring the public against the discomfort attendant the use of a dull cannula and the risk of infection due to careless sterilization.

In accordance with my invention, I provide cartridge syringes with cannula gripping chucks, locked or released by means of a closing sleeve threaded on the syringe tip. The chuck jaws may be either a part of the sleeve or a part of the syringe tip, although the former construction is preferred as it enables the many cartridge syringes, now in use, to be readily converted, at low cost, to receive the cannulae that my invention makes possible. For like reasons, it is preferred that the chuck jaws be formed as an in-

2

tegral part of a chuck element to be attached to a closing sleeve or a syringe tip, as may be desired.

In the accompanying drawings, I have shown 5 illustrative embodiments of my invention from which these and other of its novel features and advantages will be readily apparent.

In the drawings:

Fig. 1 is a fragmentary view, in elevation, of a 10 cartridge syringe in accordance with my invention.

Fig. 2 is a section along the lines 2—2 of Fig. 1.

Fig. 3 is a perspective view of a chuck element 15 in accordance with my invention.

Fig. 4 is a longitudinal fragmentary section 20 showing a modification of my invention.

Fig. 5 is a section, on an enlarged scale, along the lines 5—5 of Fig. 4.

Fig. 6 is a view, similar to Fig. 4, of another 25 embodiment of my invention.

Fig. 7 is a longitudinal section on an enlarged scale through the closing sleeve and chuck element of the embodiment shown in Fig. 6.

Fig. 8 is a like view illustrating the connection 30 of the chuck element to the closing sleeve, and

Fig. 9 is a section, on an enlarged scale, along the lines 9—9 of Fig. 8.

In the drawings, I have indicated at 10 a conventional cartridge syringe having an externally threaded tip 11 to which an intermediate part of a cannula is connected and through which it extends so that its pointed rear end is positioned to pierce the diaphragm 12 of a cartridge 13 when that cartridge is seated by the assembly of 35 the syringe for use.

In order that dental cannulae may consist of a predetermined length of suitable tubing 14 beveled at both ends to establish points 15 and 40 16, I provide cartridge syringes with chuck means adapted to grip any intermediate part of the cannula and to be quickly and easily operated to ensure maximum convenience to the user in attaching a cannula to a cartridge syringe or in 45 releasing it therefrom.

In Figs. 1 and 2, I have shown a cartridge syringe 10 of the type now widely used as evidenced by the head shell seat 17 at the front end of the cannula receiving bore extending through 50 the syringe tip 11. Threaded on the tip 11 is a closing sleeve 18 having a chamber 19, the port 20 at the front end of which is forwardly and inwardly tapered but which is dimensioned to receive freely the cannula 14.

55 Housed by the closing sleeve is a chuck element

generally indicated at 21 which I have shown as consisting of a cylindrical body having a bore therethrough which freely receives the cannula 14. As may be most clearly seen in Fig. 3, the body is tapered at its front end as at 22 and is cut from its front end rearwardly a substantial distance to establish a plurality of resilient jaws 23 interconnected at their rear end. As a matter of preference, I provide each chuck element 21 with four such jaws. The free ends of the jaws 23 are dimensioned to fit the port 20 in the closing sleeve and are compressed thereby to grip the cannula 14 as the closing sleeve 18 is threaded on the tip 11.

Such cannula attaching means are simple and inexpensive to produce and ensure an adequate grip on the cannula but for maximum convenience to the user, I prefer that each chuck element 21 be a part of either the syringe tip or the closing sleeve.

In Fig. 4, I have shown the syringe tip 24 as being of slightly greater diameter than the tip 11 and as having a counter bore 25 dimensioned to receive the cylindrical extension 26 which is an integral part of but of greater diameter than the body of the chuck element 21. The extension 26 thus establishes a shoulder by which the chuck element 21 may be locked to the tip 24 as by upsetting its extremity as at 27. The closing sleeve 28 is substantially similar to the closing sleeve 18 except as to its cross sectional shape and as to dimensions as required by the size of the tip 24.

In Figs. 6-9, I have shown a further embodiment of my invention in which the chuck element 21 is attached to the closing sleeve. For this purpose, I have shown a closing sleeve 29 having a chamber 30 with its front part tapering towards its cannula receiving port to provide surfaces 31 engageable with the chuck jaws 23 to compress them against the cannula 14 as the closing sleeve is threaded on the syringe tip 11.

The closing sleeve 29 is also shown as having a counterbore 32 and internally threaded for attachment to the syringe tip 11. The chuck element 21 of this embodiment has an integral extension 33 of lesser diameter than its body thereby to establish a shoulder 34, and in Fig. 8, I have indicated a tool 35 having a concave work engaging face 36 by which the shoulder established by the counterbore 32 may be upset, as shown at 37 in Fig. 7, to slidably connect the chuck element 21 to the closing sleeve.

The closing sleeve 29 illustrates a preferred construction whether the chuck element 21 is connected thereto, to the syringe tip, or, as shown in Figs. 1 and 2, is separate therefrom but confined therebetween. As will be apparent from Fig. 7, I provide the cannula receiving port 38 as a forwardly and outwardly disposed taper with its inner extremity dimensioned to receive the cannulae but of substantially lesser diameter than the outer extremity of the forwardly and outwardly tapering mouth 39 of the cannula receiving passage 40 through the chuck element 21.

This construction of the closing sleeve and chuck elements is important as it avoids any difficulty in inserting the cannula into the closing sleeve and ensures that the cannula, when thus inserted, enters the chuck element 21 without the necessity of hunting for its entrance.

While it is obvious that each closing sleeve must be formed to enable it to be firmly engaged and readily rotated by the user, the cross sectional shapes of the closing sleeves shown in Figs. 5

and 9 are extremely satisfactory in use. The taper of the jaw closing surfaces of the closing sleeves is, of course, that which results in the secure clamping of a cannula with minimum rotating of the sleeve.

From the foregoing, it will be apparent that dental syringes equipped with my chuck means are extremely satisfactory in use since they are easily operated and ensure a tight grip on dental cannulae thereby eliminating the expense hitherto entailed in completing such cannulae by the addition of head shells thereto.

What I therefore claim and desire to secure by Letters Patent is:

1. In a cartridge syringe, a tip member, a closing sleeve member having forwardly and inwardly inclined surfaces at the front end of its chamber and being threaded on said tip member, and a chuck element including a plurality of resilient jaws of substantial length interconnected at their rear ends to establish a cylindrical part and disposed to have their front ends engaged and compressed by said surface as said members are threaded together, said cylindrical part and one of said members including complementary portions locking them together.

2. In a cartridge syringe, an externally threaded tip member having a recess, a closing sleeve member threaded on said tip, and a chuck element including a plurality of resilient jaws interconnected at their rear ends to establish a cylindrical part and including an integral extension at its rear of greater diameter than said part defining a shoulder, said extension being seated in said recess and locked to said tip, the front end of said jaws and said sleeve member having mutually engageable portions disposed to effect the compression of said jaws as said members are threaded together.

3. The cartridge syringe of claim 2 in which portions of the tip at the mouth of its recess are disposed to engage the shoulder established by the junction of the cylindrical part and the extension of the chuck element.

4. In a cartridge syringe, an externally threaded tip member, a closing sleeve member threaded on said tip member, and a chuck element including a plurality of resilient jaws interconnected at their rear ends to establish a cylindrical part and including an integral, rearwardly disposed extension of lesser diameter than said part to establish a shoulder, and means in said sleeve member freely receiving said extension but engageable by the shoulder defined by the junction of said part and said extension thereby to slidably connect said chuck element to said sleeve member, the front portions of said jaws being disposed to be forced towards each other by said sleeve member as it is threaded on said tip member.

5. The cartridge syringe of claim 4 in which the means in the sleeve member comprises an internal shoulder intermediate its ends.

6. In a cartridge syringe for use with a cannula pointed at both ends, a tip, a closing sleeve threaded on said tip and having a chamber and a cannula receiving port at its front end in communication therewith, said chamber having forwardly and inwardly inclined surfaces adjacent said port and said port being forwardly and outwardly tapered, and a plurality of resilient jaws intermediate said tip and said sleeve normally spaced to establish a cannula receiving passage and disposed to be forced towards each other by said closing sleeve surfaces as said sleeve is threaded on said tip thereby to clamp the

cannula, the inner surfaces of said jaws being outwardly and forwardly tapered at their front ends to establish a passage mouth, the cross sectional area of which at its outer extremity is greater than that of the inner extremity of said port.

DAVID C. WILLIAMS.
